UNITED STATES PATENT OFFICE.

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

CAR-VESTIBULE DIAPHRAGM.

1,095,762.

Specification of Letters Patent.

Patented May 5, 1914.

Application filed January 12, 1914. Serial No. 811,519.

To all whom it may concern:

Be it known that I, EDWARD E. WHITMORE, a citizen of the United States, residing at Chicago, in the county of Cook and 5 State of Illinois, have invented certain new and useful Improvements in Car-Vestibule Diaphragms, of which the following is a specification.

In railway car construction, as is well 10 known, the vestibules of adjacent cars are closed in by a flexible diaphragm arranged at the two sides of and above the platform, this diaphragm being of the accordion type and connected at one extremity 15 to the end plate of its car and at the other extremity to the face plate which yieldingly bears against the face plate of the adjacent car of the train.

The diaphragm as an entirety has the 20 form of an inverted U comprising a roof portion and side walls or legs. In connection with other features of car construction it is preferable that the lines defining the diaphragm above shall be substantially 25 horizontal, but by reason of the fact that water is not readily shed by the flat roof of a diaphragm and consequently the moisture penetrates the seams and the material itself and thus causes rapid deterioration, it 30 has been proposed to avoid this difficulty by forming the roof with a medium ridge from which the folds of the diaphragm provide channels extending with a decided pitch to both sides. It has also been suggested to 35 arrange above a flat roof, a fly or hood the folds of which provide channels extending at a downward inclination from a median ridge. Neither of these expedients has been found to be entirely satisfactory if in either 40 case the roof of the diaphragm, whether integral with the sides or separate therefrom as a hood, has the undesirable median ridge with channels defined above by laterally sloping lines.

45 The principal object of the present invention is therefore the improvement of the accordion type of diaphragm construction in such manner as to provide a roof portion the folds of which along their upper edges are 50 defined by horizontal lines and the bottom or trough of which has a decided pitch from the median line toward each side. The same object may be in a measure attained, though in a less advantageous way by applying to 55 a flat roof diaphragm of the ordinary type

a supplemental roof in the form of a fly or hood having the improved characteristics above described, that is to say, with the upper portion of the folds horizontal while the bottoms or troughs of the fold have a 60 lateral pitch.

In the carrying out of the inventive idea referred to I find it advantageous to employ that form of shoulder construction set forth in Patent No. 1,078,758 as it enables the 65 efficient and economic use of diaphragm folds of the U-cross section, and as applied to a supplemental roof or hood, imparts thereto the desirable downward deflection at the sides which characterizes the hood construction of Patent No. 1,078,757.

In order that the invention and its manner of application may be readily understood the same is set forth in the accompanying drawing and in the description based thereon as embodied in an integral and also in a supplemental roof for diaphragms. As, however, the invention is susceptible of modification within wide range to adapt it for embodiment in other constructional 80 forms the drawing and description are to be taken in an illustrative and not in an unnecessarily limiting sense.

In the drawing—Figure 1 is a front elevation of such a diaphragm with the face 85 plate removed; Fig. 2 is a side elevation of the upper portion of a diaphragm embodying the invention; Fig. 3 is a vertical longitudinal section taken through the upper portion of a car diaphragm illustrating the invention as applied to a supplemental roof in the form of a hood; and Fig. 4 is a vertical transverse section taken on the line 4—4 of Fig. 3.

Having reference to Figs. 1 and 2 more particularly, the reference numeral 11 designates the car end plate between which and the diaphragm face plate 12 is arranged an accordion plaited diaphragm comprising in the present case two folds. The legs of the diaphragm indicated generally at 13 are connected above by a roof portion indicated at 14 and shoulder pieces 15. By reference to said Figs. 1 and 2 it will be seen that each fold of the roof portion 14 provides a channel 16 extending transversely from the median line of the roof, said channel being defined above by substantially horizontal lines formed by the meeting edges 17 of the folds, while the bottom of troughs 18 of 110

said channels have a decided pitch laterally from the median line of the roof. It will also be observed that the shoulder pieces 15 which are composed of similar folds form continuations of the channels 16, the trough of each shoulder piece having a greater pitch than the trough 18 of the roof, while the said shoulder pieces are outwardly defined at 19 by curved lines forming a quadrant to 10 which the outer lines of the roof and of the legs 13 are tangent, and the lower ends of the shoulder pieces being connected to the folds of the legs which form continuations thereof.

15 In Figs. 3 and 4 the construction is substantially the same except that the invention is embodied in a supplemental roof superposed above a flat roof. Herein for purposes of illustration the diaphragm is shown 20 as composed of legs 21, shoulder pieces 22, and a roof 23, the folds of which are of V cross-section as distinguished from the U cross-section illustrated in Figs. 1 and 2. Above the roof 23 and shoulder pieces 22 25 the hood or supplemental roof is supported between retaining strips 24, 25, suitably secured to the end plate 11 and the face plate 12. This supplemental roof is identical with the integral roof shown and described with 30 reference to Figs. 1 and 2 possessing the characteristic feature that the lines defining the upper edge of the folds are horizontal while the troughs of the same have a decided lateral pitch from the median line of 35 the roof and are continued outwardly by the folds of the shoulder pieces which are defined outwardly by curved lines and the troughs of which have a greater pitch than the troughs of the roof folds. The shoulder 40 pieces forming the outer margins of the roof provide a terminal downward deflection which gives the desired hooded effect so as to more effectively exclude the dust and cinders, as well as gusts of air from 45 entering beneath the hood and lodging upon the inner roof or by their violence turning the hood inside out, or tearing it from its fastenings.

By the invention as above described it 50 will be observed that a roof is provided which has a decided pitch laterally from the median line and which at the same time preserves the horizontal lines extending transversely of the diaphragm roof so as to 55 enable the employment of a flat topped diaphragm and yet provide for the efficient shedding of water.

Another advantage of the improved construction is that the channels of the roof 60 have a cross sectional area progressively increasing from the median line toward the side and that the walls of the folds forming such channel progressively increase in transverse dimensions at points more remote from said median line, thus increasing

the capacity for expansion where the roof is an integral part of the diaphragm instead of being supplemental thereto.

In the operation of trains and particularly when rounding curves the diaphragm 70 folds upon the outer side of the curve are expanded while those upon the inner side are contracted, the movement being analogous to that about a vertical pivot arranged in the median plane of the diaphragm. 75 Applicant's construction, it will be seen, provides for greater capacity of expansion in the roof portion adjacent the sides than at the center by employing folds the walls of which have greater transverse dimensions at points more remote from the median line.

I claim:

1. A car vestibule diaphragm of the accordion type including a roof as an integral 85 part thereof, the folds of which are defined above by lines having a substantially less pitch than the troughs of the folds, substantially as described.

2. A car vestibule diaphragm of the accordion type including a roof as an integral 90 part thereof, the folds of which are defined above by substantially horizontal lines with troughs having a lateral pitch from a median ridge, substantially as described.

3. A car vestibule diaphragm of the accordion type including a roof as an integral 95 part thereof, the folds of which are of U cross section and defined above by substantially horizontal lines with troughs having 100 a lateral pitch from the median ridge, substantially as described.

4. A car vestibule diaphragm of the accordion type including a roof as an integral 105 part thereof, the folds of which form channels extending laterally from the median line, said channels having a cross sectional area progressively increasing from said median line toward the sides, substantially as described.

5. A car vestibule diaphragm of the accordion type including a roof as an integral 115 part thereof, the folds of which form channels extending laterally from the median line, the walls of the channels progressively increasing in transverse dimensions at points more remote from said median line, substantially as described.

6. A car vestibule diaphragm of the accordion type including a roof as an integral 120 part thereof, the folds of which form channels extending laterally from the median line, the walls of the channels progressively increasing in transverse dimensions at points more remote from said median line, the said channels defined above by substantially horizontal lines and their troughs having a lateral pitch, substantially as described.

7. A car vestibule diaphragm of the accordion type including a roof, the folds of 125

which are defined above by lines having a substantially less pitch than the troughs of the folds, and shoulder pieces forming an outer continuation of the folds, the folds of 5 the shoulder pieces having troughs of a greater pitch than the troughs of the roof folds, substantially as described.

8. A car vestibule diaphragm of the accordion type including a roof, the folds of 10 which are defined above by lines having a substantially less pitch than the troughs of the folds, and shoulder pieces forming an outer continuation of the folds, the folds of 15 the shoulder pieces having troughs of a greater pitch than the troughs of the roof folds, and outwardly defined by curved lines to which the upper lines of the roof are tangent, substantially as described.

9. A car vestibule diaphragm of the 20 accordion type including a roof, the folds of which are defined above by substantially horizontal lines with troughs having a lateral pitch from a median ridge, and shoulder pieces forming an outer continuation of

the roof folds, the folds of the shoulder 25 pieces having troughs of a greater pitch than the trough of the roof folds, substantially as described.

10. A car vestibule diaphragm of the accordion type including a roof, the folds of 30 which are defined above by substantially horizontal lines with troughs having a lateral pitch from a median ridge, and shoulder pieces forming an outer continuation of the roof folds, the folds of the shoulder 35 pieces having troughs of a greater pitch than the trough of the roof folds, and outwardly defined by lines forming a quadrant to which the outer lines of the roof and sides are tangent, substantially as described. 40

In testimony whereof I have hereunto signed my name in the presence of two subscribing witnesses.

EDWARD E. WHITMORE.
